UNITED STATES PATENT OFFICE.

WILLIAM B. SHEFFIELD, OF KANSAS CITY, MISSOURI.

AUTOMATIC INK-DISTRIBUTER FOR PRINTING-PRESSES.

No. 909,339.

Specification of Letters Patent.

Patented Jan. 12, 1909.

Application filed September 9, 1907. Serial No. 391,864.

To all whom it may concern:

Be it known that I, WILLIAM B. SHEFFIELD, a citizen of the United States, residing at Kansas City, in the county of Jackson and 5 State of Missouri, have invented certain new and useful Improvements in Automatic Ink-Distributors for Printing-Presses, of which the following is a specification.

My invention relates to improvements 10 in automatic ink-distributors for printing-presses, and my object is to obtain a more uniform distribution of ink on the rotary disks of job-presses than has heretofore been had. I attain this object by interposing a 15 roller between the ink-fountain and the customary form rollers of the press. This roller is carried up to the ink-fountain, receives a supply of ink therefrom, and then distributes the same uniformly upon the disk so that 20 when the form rollers pass over the same they will be evenly and thinly coated. The result is that the type over which the form rollers pass is evenly coated with ink instead of becoming clogged therewith as is frequently the 25 case where one of the form rollers takes its supply directly from the ink-fountain, as in the latter instance it does not have time to properly distribute the ink before running over the form of type.

30 Referring now to the accompanying drawings, which illustrate the invention, Figure 1 represents a broken side elevation of the upper portion of a job-press provided with my improvements. Fig. 2 is a view of the same 35 looking in the direction of arrow *a*, Fig. 2.

1 designates the frame of the press, 2 the bed thereof for receiving the form of type, 3 a pair of rocker-arms, 4, rods yieldingly-carried by the rocker-arms, 5 the form rollers 40 which are journaled in bearings 6 carried by rods 4, 7, a rotary inclined disk, 8 and 9, a ratchet-wheel and pawl, respectively, forming part of the gearing for rotating the disk, and 10, a track the rails of which are at opposite 45 sides of the lower portion of the disk.

All of the above parts are old in the art and form no part of the present invention, which consists of the parts hereinafter described.

11 designates an independent ink-distributing roller adapted to pass up and down over the face of the disk for the purpose of supplying ink thereto and to assist in distributing the ink thereon. Said roller is provided with a shaft 12 mounted in a pair of 55 wheels 13, which pass upon the track as the roller approaches the end of its downward

movement and raises the same above the disk so that said disk may rotate without injuring the surface of the roller, which, preferably, consists of the composition from 60 which ink-distributing rollers are usually made. The downward movement of the independent roller 11 is limited by a pair of loops 14 contacting with a pair of stops 15 at the undersides of the rails forming track 10. 65 As roller 11 does not pass downward over the form of type there is no danger of it conflicting with the grippers of the press, hence it is made larger in diameter than the form rollers to increase its effectiveness in distributing the ink upon the disk. 70

Loops 14 straddle wheels 13 and are loosely mounted upon shaft 12, so that when the latter rotates with the roller the loops will not turn therewith but will depend therefrom 75 and thus be in position to pass under the pointed ends of the track and engage stops 15 when the roller moves downward to the position shown in Fig. 1.

Roller 11 is carried upward to an ink-fountain 80 20, at each oscillation of rocker-arms 3 by a pair of arms 16 secured by bolts 17 to eyes 18 on bearings 6, as shown in Figs. 1 and 2. The upper ends of arms 16 have notches 19 which are carried up into engagement 85 with shaft 12 and push the same, together with the independent roller 11, upwardly over the surface of disk 7 until said roller contacts with and receives a supply of ink from a feed-roller 21, forming part of the ink-fountain above referred to. Then when the rocker-arms 3 carry arms 16 downward the latter will guide the independent roller over the face of the disk so that it may distribute 90 the ink thereon, which ink is further distributed upon the disk when the independent roller and the form rollers again travel upward over the face of the disk. As the form rollers pass over the disk the second time they not only assist roller 11 in evenly distributing the ink upon the face of the disk, 95 but take up a thin coating of ink and carry the same over the face of the type, locked in the form (not shown) carried by bed 2. The above operation is repeated each time the 100 rocker-arms 3 oscillate.

By mounting roller 11 in the manner shown and described it may be instantly removed from the press when it is desired to wash the ink from the face of disk 7 and the 110 roller.

By taking the ink from the fountain and

distributing it over the face of the disk with the independent roller prior to coating the form rollers, it is evident the latter will receive a more uniform coating of ink than if 5 permitted to pass directly to the fountain for their supply, in which instance it is obvious that the foremost roller would receive a thicker coating than its companions, and before it could evenly distribute the ink upon 10 the disk would carry an excess thereof over the form of type and coat the same too heavily.

While I have shown my preferred means for operating and controlling the independent ink-roller 11, I, of course, reserve the right to make such changes as properly fall within the spirit and scope of the appended 15 claims.

Having thus described my invention, what 20 I claim is:—

1. The combination with a printing-press provided with a rotary disk, a bed and the customary form rollers which latter are adapted to travel over the disk and the bed, 25 an independent ink-distributing roller, a pair of members traveling with the form rollers which carry the independent roller upon the disk to the ink-fountain, and means on the press for checking the movement of the distributing roller before it reaches the bed.

2. The combination with a printing-press provided with an inclined rotary disk, a bed and the customary form rollers which latter are adapted to travel over the disk and the 30 bed, of an ink-fountain located above the upper portion of the disk, an independent ink-distributing roller, a pair of notched arms secured to the bearings of the form rollers adapted to engage the shaft of the independent roller and carry the same up the disk to the ink-fountain, and means on the 35 press for checking the movement of the distributing roller before it reaches the bed.

3. The combination with a printing-press 40 provided with a bed, an inclined rotary disk, a track near the lower end of the disk, and the customary form rollers adapted to travel over the disk and the bed, of an ink-fountain located above the upper portion of the disk, 45 an independent ink-distributing roller which

travels up the disk with the form rollers and supplies ink from the fountain to the disk, and means carried by the independent roller which engage the track and limit the downward movement of said independent roller. 55

4. The combination with a printing-press provided with a bed, an inclined rotary disk, a track near the lower end of the disk, and the customary form rollers adapted to travel over the disk and the bed, of an ink-fountain 60 located above the upper portion of the disk, an independent ink-distributing roller which travels up the disk with the form rollers and supplies ink from the fountain to the disk, and a pair of loops carried by the independent roller adapted to engage the track and limit the downward movement of said independent roller. 65

5. The combination with a printing-press provided with a bed, an inclined rotary disk, a track near the lower end of the disk, and the customary form rollers adapted to travel over the disk and the bed, of an ink-fountain 70 located above the upper portion of the disk, an independent ink-distributing roller which travels up the disk with the form rollers and supplies ink from the fountain to the disk, and a pair of wheels at the ends of the independent roller which travel upon the track and lift the roller from the lower portion of the 75 disk, and means on the press for checking the movement of the distributing roller before it reaches the bed.

6. The combination with a printing-press provided with a rotary disk, a bed, rocker- 85 arms, and the customary form rollers which are carried over the disk and the bed by said rocker-arms, of an ink-fountain located above the disk, an independent ink-distributing roller which is carried over the disk with the 90 form rollers, and means on the press for checking the movement of said distributing roller before it reaches the bed.

In testimony whereof I affix my signature, in the presence of two witnesses.

WILLIAM B. SHEFFIELD.
